UNITED STATES PATENT OFFICE

122,104

DESIGN FOR A HAT BAND

Julius Wolf, Cheltenham, Pa.

Application April 12, 1940, Serial No. 91,620

Term of patent 3½ years

To all whom it may concern:

Be it known that I, Julius Wolf, a citizen of the United States, residing at Cheltenham, in the county of Montgomery and State of Pennsylvania, have invented a new, original, and ornamental Design for a Hat Band, of which the following is a specification, reference being had to the accompanying drawing, forming a part thereof, and in which

Fig. 1 is a perspective view of one side of a hat band showing my new design; and

Fig. 2 a perspective view of the other side thereof.

I claim:

The ornamental design for a hat band, as shown.

JULIUS WOLF.
